UNITED STATES PATENT OFFICE.

JAMES ADAMS CHARTER, OF BELOIT, WISCONSIN, ASSIGNOR OF ONE-HALF
TO JOHN CHARTER, OF STERLING, ILLINOIS.

GOVERNOR FOR GAS-ENGINES.

SPECIFICATION forming part of Letters Patent No. 542,043, dated July 2, 1895.

Application filed November 20, 1894. Serial No. 529,391. (No model.)

To all whom it may concern:

Be it known that I, JAMES ADAMS CHARTER, a citizen of the United States, residing at Beloit, in the county of Rock and State of Wisconsin, have invented certain new and useful Improvements in Governors for Gas-Engines, of which the following is a specification.

My invention relates to gas-engines, and consists in means for regulating the same by controlling the exhaust and in means for properly supplying and regulating the supply of volatile liquid, as fully set forth hereinafter and as illustrated in the accompanying drawings, in which—

15 Figure 1 is a longitudinal sectional elevation of sufficient of a gas-engine to illustrate my improvement. Fig. 2 is a plan view of the crank-shaft and connections. Fig. 3 is a detached elevation, in part section, of the inlet-valve casing and adjuncts.

The engine has a cylinder A, mounted upon a suitable base B, with supports for a crank-shaft G, the connecting-rod (not shown) being connected to a piston W in the cylinder A, which has an inlet-port *a* and an exhaust *b* near the rear end of the cylinder. These parts are so constructed, arranged, and operated that as the piston moves forward it draws in a charge of gas and air. As it moves back it compresses the same. The charge is then exploded and the piston moves forward and drives the crank, and the exhaust valve is then opened as the piston moves back and exhausts the spent gases from the engine-cylinder. Heretofore the regulation of this class of engines has been accomplished through the medium of devices which are generally somewhat complex, delicate in operation, and liable to get out of order, and always expensive to 40 construct.

One object of my invention is to effect the desired regulation without the use of complex appliances, and to this end I make use of devices which I will now describe.

45 The exhaust-valve H is seated in the exhaust-casing *b'*, so as to normally close the exhaust-port, a spring *p* bearing upon a washer *z* of the exhaust-valve stem 4 and tending to hold the exhaust-valve in its seat. A rod C is mounted in suitable bearings, so as to slide

to and from the exhaust-valve stem 4, and the said rod has a roller or projection *f*, arranged opposite the edge of a cam D upon a shaft 5, the said cam having a toe or projection 6. The shaft 5 is geared by means of gears E F 55 with the crank-shaft G, the gear F on the crank-shaft being one-half the circumference of that upon the shaft 5, so that there will be two revolutions of the crank-shaft to one revolution of the shaft 5, and consequently the toe 60 or projection 6 of the cam D will be brought against the roller *f* to push in the rod C and valve-stem 4 and open the exhaust-valve once to each two revolutions of the crank-shaft.

In the casing I, which communicates with 65 the inlet-port *a*, is a self-acting or check valve J, which is normally held in its seat under a comparatively-slight pressure by means of a spiral spring 7, coiled around the stem of the valve and bearing upon the end of the washer 70 at the end thereof, the said spring exerting only sufficient pressure to prevent the valve J from lifting by the outflow of the spent gases when the exhaust is open.

It will be evident that if the exhaust-valve 75 is closed when the piston W moves forward the piston will draw in a charge of gas and air through the port *a*, lifting the valve J; but if the exhaust-valve H is opened at the time the piston moves forward then the air will 80 draw in through the port *b* and there will be no indraft of the mixed charge of gas and air through the port *a*, and consequently the engine will run without a charge and without explosion. I take advantage of this fact to 85 avoid the use of appliances for governing the flow of the volatile liquid and to avoid the introduction of an explosive whenever the engine acquires an undue rate of speed, effecting these results by holding open the valve 90 H. For this purpose I make use of a suitable governing device and of a detent, which will be thrown in position to hold open the valve by the action of the governor when the speed of the engine becomes too rapid, the detent 95 being released when the speed is reduced. Different appliances may be employed; but, as shown in Figs. 1 and 2, there is a sleeve P, sliding on the crank-shaft G and provided

with a flange or collar *v*, and this sleeve is 100

connected by a pin 13 with the crank-arms 8 8 of the governor Q, the balls 9 9 on the governor being connected by a spring 10.

To a bracket 33, connected to the frame of 5 the engine, is pivoted a lever T, having at one end a friction-roller 31, the other end being beveled and adapted to engage the grooved periphery of a roller f' upon the rod C, turning upon a stud in line with the stud of the 10 roller f.

In operation the toe 6 of the cam D will always push in the rod C sufficiently to permit the beveled end of the lever T to be swung into position opposite the grooved edge of the 15 roller f', a result which will take place if the engine moves too fast, causing the balls of the governor to fly out and carrying outward the sleeve P, bringing its flange D to bear against the roller at the end. When the toe of the 20 cam D leaves the roller f, the roller f' will engage the end of the lever T, which acts as a detent and holds the valve H open. When the speed begins to slacken, the balls of the 25 governor will draw together and the sleeve P will be thrown inward; but this will not immediately alter the position of the detent, which is important, as it is desirable to keep the valve H open until the speed is sufficiently reduced. When, however, the toe 30 of the cam D next makes contact with the roller f, it will force the roller f' away from the end of the lever T, when a spring 32 will draw the outer end of the lever T against the flange v, carrying the other end from opposite the roller f', when the operation will proceed as before.

The device above described may be used in connection with an engine which is supplied with both gas and air or in connection with 40 engines in which there is a volatile fluid supplied, the latter being shown.

In the construction shown the casing I has an inlet-pipe N, communicating with a reservoir L, arranged at one side of the casing I. 45 The inlet-pipe has an inturned end, the top of which may be on a level with the end of an outlet or overflow pipe M, extending through the bottom of the casing; or the inlet-pipe may extend very slightly above the level 50 of the said pipe M, as shown in Fig. 3, so that the liquid in the inlet-pipe will always be at a point level with or but slightly below the end of the pipe M, and whereby any upflow of air through the casing I and through the 55 pipe 16 will readily carry with it the liquid from the pipe N.

In order to govern the amount of liquid which is lifted at each outward stroke of the

piston, I provide the pipe N with a valve K, which will regulate the flow with great nicety. 60

The reservoir L is supplied with oil by means of a pump. Thus there is a reservoir R, from which the pipe M extends upward. Another pipe 17 extends from the bottom of the reservoir to the inlet-valve casing 18 of a 65 pump S, and a pipe 19 20 extends to a port 21 of the reservoir L. By this arrangement the pump S may be maintained in continuous operation, drawing the oil from the reservoir R and forcing it into the reservoir L, and the 70 latter always having the same quantity in it, any excess flowing out through the pipe M into the reservoir R.

The pump S may be operated in any suitable manner. As shown, the plunger of the 75 said pump is connected by a connecting-rod 22 with a wrist-pin 23 upon the side of the cam D of the shaft E.

It will be seen that by holding open the exhaust when the speed of the engine becomes 80 too great I prevent the passage of any air-current through the air-chamber and along the fluid-inlet pipe N without the use of any appliances or means for regulating the flow of the fluid or of the air through the air-chamber. I thus avoid the means of governing the oil or the inflowing air that has heretofore been necessary.

Without limiting myself to the precise construction and arrangement of parts described, 90 I claim as my invention—

1. The combination with the exhaust valve of a gas engine, of a rod C carrying rollers f, f', the latter being grooved, a detent for engaging the latter roller, a governor controlling 95 the detent, and a cam for engaging the roller C, substantially as described.

2. The combination with the inlet valve casing I of a gas engine, of an inlet pipe having an upturned end, a reservoir L, communicating with said pipe, an overflow pipe M from said reservoir with its end below but nearly level with that of the inlet pipe, a reservoir R communicating with the pipe M and a pump S with a pipe leading from the reservoir R to pump S, and another pipe leading from the pump S to the reservoir L, substantially as set forth.

In testimony whereof I have signed my name to this specification in the presence of 110 two subscribing witnesses.

JAMES ADAMS CHARTER.
